RESILIENT GARMENT-SUPPORTING HOOP
AND GARMENT

Corena S. Ser Vaas, Indianapolis, Ind.

Application November 4, 1952, Serial No. 318,541

4 Claims. (Cl. 2—52)

1

This invention relates to an improved garment-supporting hoop and to the combination thereof with the supported garment. This application is a continuation-in-part of my prior copending application Serial No. 27,745, filed May 18, 1948.

It has heretofore been proposed to support a garment, such as an apron, by inserting through a loop or casing in the garment at the waistline thereof a bent spring such as a flat metal spring which may be placed about the waist of the wearer and retains itself and the garment thereon by tightly embracing the waist of the wearer.

It is an object of my invention to provide an improved garment supporting hoop. It is an object of my invention to provide such a hoop which will initially fit the wearer comfortably without cutting into the body at any point and which will automatically adjust itself to fit its wearer with a limited pressure or tension less than its initial pressure or tension, which will be readily insertable and removable from the garment with no tendency to wear or poke through the material of the garment, which may be removed or left in the garment for laundering as the user may desire and as the construction of the garment may require, and which will be readily adjustable by the user to different sizes.

In accordance with my invention, I make the hoop of a plastic material having predetermined characteristics, and in a particular shape. The particular material used is a synthetic plastic material characterized by high resiliency or tendency to return to its normal shape after extreme deformation, and characterized by its ability to relax under tension and moderate temperature to take a new normal position, so that in use, in tension about the waist of the wearer, and under the influence of the body heat, it will assume a shape and size to fit the wearer with a perfect fit while still embracing the wearer's waist with a limited pressure or tension sufficient to hold the garment snugly and properly in place.

Prior metal devices of this type have been bent or coiled to a circular shape, which is not suited to obtain my improved result. A circular spring tends to embrace the wearer with its tightest engagement at the sides of the waist, and to engage the wearer only lightly or not at all at the front, and its ends tend to cut into the wearer at the back. In accordance with my invention I form the plastic hoop to an initial oval shape so that firm engagement occurs at the front of the wearer and over the mid-portion of the hoop, so

2

that such mid-portion is especially subjected to the body heat, and will be especially subjected to the relaxing effect which occurs in the presence of body heat. In addition, the initial length of the loop is such that in its normal initial shape its end portions overlap a substantial distance along a flattened side of the oval hoop, so that those ends are of reduced curvature or flattened with respect to the rest of the hoop, and upon initial wearing engage the wearer with progressively decreasing pressure toward the ends of those portions, and so that such ends are subjected to a progressively decreasing extent to tension under the influence of the body heat.

By plastic material I mean the generally accepted current meaning of that term, indicating a rather broad class of synthetic, thermosetting or thermoplastic, organic materials. The plastic materials which I use have a number of advantages for use as garment-supporting hoops. They are light in weight, highly resilient, present a smooth surface having little or no abrasive or wear effect on fabrics, are relatively unbreakable, are substantially inert so that they neither rust nor corrode and produce no harmful reaction on the skin. They are not deformed by heat in the absence of sustained deforming force and not affected by water or by soaps or detergent, so that garments containing the hoops may be laundered by usual home laundry methods. They have a pleasing feel and warmth which especially distinguishes them from metal. In addition, such plastic materials have certain properties which are peculiarly and especially advantageous in a garment support. A desired high resilience and low tension is readily obtained in a strip of such material of relatively large cross section and body, i. e., the hoop can be made to be easily elastically deformable and to have soft or low-spring-rate spring characteristics, which not only reduces any tendency for the hoop to cut into the skin but which permits the cross section to be rounded and permits the hoop to have bluntly rounded ends. The relatively large cross section and blunt ends and edges permits the ring to be inserted in a hem or casing in which it fits with a tight fit, without danger of cutting or poking through the material of the garment, and which tends to hold the garment in place on the hoop.

Among the class of plastic materials, I prefer to use a cellulose acetate or cellulose acetate-butyrate plastic or plastic materials of corresponding characteristics, and I prefer to use such materials in an H hardness grade.

The initial shape of a hoop embodying my invention is desirably oval or elliptical, with the ends of the strip of plastic material overlapping over the major portion of one of the flattened sides of the oval and extending symmetrically in opposite directions from the minor axis of the oval. I preferably use an oval in which the major axis is from about 15% to about 25% longer than the minor axis, and I overlap the ends over a length of about 25% of the circumference of the normal shape of the hoop. The initial size of the hoop is such that on the intended wearer the hoop will be resiliently opened to bring the ends out of overlapping relation and desirably spaced an inch or two from each other.

To make such a hoop, I preferably use a strip of generally rectangular cross section having substantially greater width than thickness, preferably with a width to thickness ratio of about 3 to 1, and of such size that it exerts a resilient pressure of about one pound between its ends when resiliently deformed to a position, comparable to a normal fit position, in which its ends are no longer overlapping and are separated from each other, say by about 4 inches. Illustratively, for a "medium" size hoop, I use a strip approximately 28" long, formed to an oval shape with its major axis about 7½" and its minor axis about 6½" and with its ends overlapping about 5" along a flattened side, and with the material about $\frac{1}{8}$ inch thick and $\frac{1}{2}$ " wide, so that when the ends are drawn apart a distance of 4" they exert a pressure toward each other of about one pound. Other sizes are of corresponding shape and have a corresponding overlap, so that the pressure between the ends when drawn 4" apart remains at about one pound.

The accompanying drawing illustrates my invention. In such drawing,

Fig. 1 is a plan view of a hoop embodying my invention;

Fig. 2 is a cross-sectional view taken on the line 2—2 of Fig. 1; and

Fig. 3 is a partial view of the upper edge of an apron with my improved hoop in place in a hem or casing formed at such edge.

The hoop shown in the drawing is a hoop being sold commercially in large quantity. The hoop 10 is made of a strip of cellulose acetate material desirably containing a minor proportion of white or other colored filler and a minor proportion of plasticizer, such material being obtained commercially under the trade-name "Tenite I." Hoops may also be suitably made of cellulose acetate-butylate plastic materials, such as that available commercially under the trade-name "Tenite II." Other corresponding plastic materials may also be used. The plastic material is extruded in strip form having a rectangular cross section about .165" thick and about .500" wide, with slightly rounded corners. The strip is cut to length—about 24" for a "small" size, about 28" for a "medium" size and about 33" for a "large" size. The lengths are so proportioned that the ends of a properly fitting hoop will have no overlap when worn and desirably will be spaced an inch or two from each other. The ends 23 and 25 of the strip are bluntly rounded, as by mechanical stock-removing methods. The strip is then heated, as to about 100° C., bent to shape around an oval form, with its end-portions 22 and 24 overlapping about 4 inches in a "small" hoop, or more, up to about 7

inches, in a "large" hoop. The heated and bent hoop is then cooled, either artificially or in the air, while held in the formed shape. Upon cooling it retains the formed shape, substantially without any spring-out from that formed shape. The initial formed shape is an oval as shown in Fig. 1, with its major axis A 15% to 25% greater than its minor axis B and with its end portions 22 and 23 overlapping along one flattened side and over about 25% of the circumference of the oval shape. Illustratively in the "medium" hoop the major axis is desirably about 7½", the minor axis is about 6½" and the overlap about 5".

15 The formed hoop will thus have a front portion 26 and side portions 28, with the front portion of substantially less curvature than the side portions 28. It will also have rear portions 22 and 24 of substantially less curvature than the 20 adjoining portions of the hoop and which are relatively more flattened than other portions of the hoop.

When the hoop is placed about the waist of the wearer, it is resiliently sprung open to separate the ends 23 and 25 to permit those ends to pass around the waist, and the hoop is then allowed to move back toward its normal shape to resiliently embrace the waist. The ends 23 and 25, however, normally do not return to overlapping position, but are spaced apart by a distance of an inch or so. Initially, the hoop will desirably embrace the waist with a tighter pressure than is desired. With the hoop under tension, however, and influenced by body heat, the plastic material relaxes toward a new normal position, so that the pressure on the waist of the wearer is reduced to a relatively light tension. Upon removal of the hoop from the waist it resiliently recovers from its waist-embracing 40 position, but moves to the new normal position and shape, somewhat larger than the initial size, and of a shape which will vary with the wearer. By reason of this relaxing under conditions of use, the hoop soon attains a condition in which, in subsequent use, it embraces the wearer with a limited pressure, dependent upon the character of the material, and substantially independent of the initial shape to which it was formed. This result is obtained to give good fit, however, if the initial shape is oval as indicated, and smaller 50 than ultimately desired.

To support a garment such as the apron 30 on the hoop, as indicated in Fig. 3, a hem or casing 32 is formed along or adjacent the upper edge of the apron 30, as with a standard hemming device on a sewing machine, with the hem of a size to fit tightly on the hoop, especially when the apron material is pushed together along the hoop in a gathering. The hoop is then inserted by pushing one of its ends through the casing 55 32.

60 Despite the relatively tight fit, the plastic with its large cross section and rounded ends and its relative stiffness is easily inserted, without danger of cutting or poking through the material of which the casing 32 is made. Once the apron has been brought to the desired position on the hoop, with such gathering as may be desired, its tight fit on the hoop exerts a strong tendency to hold it in place, and no special provisions need 65 be made to prevent it from slipping along the hoop or off the ends of the hoop.

If the user desires to change the shape or size of the hoop, the hoop is simply heated, as in hot water, the heated hoop is then formed to the desired shape, and held in the desired new shape 70 75

while it is cooled, and it may be artificially cooled to hasten the re-forming operation.

I claim as my invention:

1. A garment supporter adapted to resiliently embrace the waist of the wearer and to retain a garment thereon, comprising a strip of plastic material having blunt ends and being of uniform generally rectangular rounded cross section having a width to thickness relation of about three to one, said supporter being shaped to a normal closed oval shape having a major axis about 15% to about 25% longer than its minor axis, and with the end portions of the strip parallel and overlapping along a flattened side of the oval shape for a distance of about 25% of the circumference of the oval, and with the oval of a size to fit the intended wearer when the hoop is resiliently opened to a position in which the ends are spaced from each other, whereby said supporter may be sprung around the waist of the wearer to resiliently embrace the waist and when so placed the initially overlapped end portions thereof will engage the waist of the wearer with progressively lighter tension toward the ends thereof and the side and front portions of the hoop will lie in firm heat-conducting relationship with the waist of the wearer, said strip material being characterized by the property of relaxing to a new normal shape under the tension imposed by said tight fit about the waist and under the influence of body heat.

2. A garment supporter adapted to resiliently embrace the waist of the wearer and to retain a garment thereon, comprising a strip of cellulose acetate material having blunt ends and being of uniform generally rectangular rounded cross section having a width to thickness relation of about three to one, said supporter being bent and set to a normal closed oval shape having a major axis about 15% to about 25% longer than its minor axis, and with the end portions of the strip parallel and overlapping along a flattened side of the oval shape for a distance of about 25% of the circumference of the oval, and with the oval of a size to fit the waist of the wearer when the hoop is resiliently opened to a position in which the ends are spaced from each other, whereby said supporter may be sprung around the waist of the wearer to resiliently embrace the waist and when so placed the initially overlapped end portions thereof will engage the waist of the wearer with progressively lighter tension toward the ends thereof and the side and front portions of the hoop will lie in firm heat-conducting relationship with the waist of the wearer, said strip material being characterized by the property of relaxing to a new normal shape under the tension imposed by said tight fit about the waist and under the influence of body heat.

3. In combination, a garment having a hem 60 adjacent one edge, a garment supporter adapted

to resiliently embrace the waist of the wearer and to retain the garment thereon, said supporter comprising a strip of plastic material having blunt ends and being of uniform generally rectangular rounded cross section having a width to thickness relation of about three to one, said supporter being shaped to a normal closed oval shape having a major axis about 15% to about 25% longer than its minor axis, and with the end portions of the strip parallel and overlapping along a flattened side of the oval shape for a distance of about 25% of the circumference of the oval, and with the oval of a size to fit the waist of the wearer when the hoop is resiliently opened to a position in which the ends are spaced from each other, whereby said supporter may be sprung around the waist of the wearer to resiliently embrace the waist and when so placed the initially overlapped end portions thereof will engage the waist of the wearer with progressively lighter tension toward the ends thereof and the side and front portions of the hoop will lie in firm heat-conducting relationship with the waist of the wearer, said strip material being characterized by the property of relaxing to a new normal shape under the tension imposed by said tight fit about the waist of the wearer and under the influence of body heat, said supporter being tightly received in the hem of the garment so that in normal use it stays in place therein but can be removed therefrom by exerting sufficient pressure.

4. A garment supporter adapted to resiliently embrace the waist of the wearer and to retain a garment thereon, comprising a strip of plastic material having blunt ends and being of uniform generally rectangular rounded cross section having a width to thickness relation of about three to one, said supporter being shaped to a normal closed oval shape having a major axis longer than its minor axis, and with the end portions of the strip parallel and overlapping along a flattened side of the oval shape, and with the oval of a size to fit the waist of the wearer tightly and in firm heat-conducting relationship therewith when the supporter is resiliently opened, said strip material being characterized by the property of relaxing to a new normal shape under the tension imposed by said tight fit about the waist of the wearer and under the influence of body heat.
